UNITED STATES PATENT OFFICE.

OLE CALUM, OF NEW YORK, N. Y., ASSIGNOR OF ONE-HALF TO PAUL HUMBERT, JR., OF NEW YORK, N. Y.

AEROPLANE.

1,121,473.

Specification of Letters Patent. Patented Dec. 15, 1914.

Application filed November 12, 1913. Serial No. 300,507.

To all whom it may concern:

Be it known that I, OLE CALUM, a citizen of the United States, and a resident of the city of New York, borough of Brooklyn, in 5 the county of Kings and State of New York, have invented a new and Improved Aeroplane, of which the following is a full, clear, and exact description.

The object of the invention is to provide a 10 new and improved aeroplane arranged to provide a large sustaining area in a comparatively small space, to insure easy rising and descending of the aeroplane, to maintain the equilibrium even in heavy sidewise 15 or contrary currents of air, and to allow safe descending in case of accident to the motor or other parts.

In order to accomplish the desired result use is made of a framework for supporting 20 the aviator, other persons, the motor and propellers, a main sustaining plane mounted on the framework and of an approximately oval shape and with the major axis thereof extending transversely, and side 25 planes arranged below the said main sustaining plane and mounted on opposite sides of the framework, the inner edges of the side planes being straight and in close proximity to the sides of the framework, and the 30 outer edges being ovoid, the front and rear ends of the side planes projecting beyond the front and rear edges of the main sustaining plane. Use is also made of a parachute normally seated on top of the main 35 sustaining plane, and springs for moving the said parachute upward into position a distance above the said main sustaining plane on the aviator releasing the normally locked parachute.

40 A practical embodiment of the invention is represented in the accompanying drawings forming a part of this specification, in which similar characters of reference indicate corresponding parts in all the views.

45 Figure 1 is a plan view of the aeroplane; Fig. 2 is a front end elevation of the same; and Fig. 3 is a sectional side elevation of the same.

The framework A of the aeroplane includes in the lower portion a suitably constructed carriage B provided with wheels C to allow of running the aeroplane on the ground preparatory to rising in the air or when descending and reaching the ground.

The carriage B is provided with suitable 55 seats D for the aviator and passengers, and the carriage also supports two motors E, E' for independently driving a front propeller F and a rear propeller F'.

On top of the framework A above the 60 carriage B is arranged a main sustaining plane G, of approximately oval shape with the major axis extending in a transverse direction and the minor axis extending longitudinally in the central longitudinal plane 65 of the aeroplane. The main sustaining plane G is arched in a transverse direction to concentrate air resistance toward the central part of the plane.

On opposite sides of the carriage B are 70 arranged side planes H and H' having their inner edges straight and in close proximity to the sides of the carriage B while the outer edges of the said side planes are ovoid. The front and rear ends of the side 75 planes H and H' project beyond the front and rear edges of the main sustaining plane G, but the sides of the main sustaining plane G project beyond the side edges of the side planes H and H', as plainly indicated in the drawings. The side planes H and H' are inclined rearwardly and downwardly, as plainly indicated in Fig. 3, so as to insure easy rising and forward traveling 80 of the aeroplane. The side planes H and 85 H' are curved from the sides of the carriage B in an outward and downward direction, but the degree of the curvature is somewhat less than that of the main sustaining plane G, as will be readily understood by reference to Fig. 2.

In order to control the rising and descending of the aeroplane use is made of front and rear elevating planes I and I' having transverse axes I², I'² journaled at 95 the sides in suitable bearings arranged on front and rear extensions A¹ and A² of the main frame A. The elevating planes I and I' are provided with upwardly-extending rods I⁴, I'⁴ connected by sets of cables or 100 other flexible connections J and J' with levers K fulcrumed on the main frame A on opposite sides of the aviator's seat D to enable the aviator to manipulate either lever K with a view to tilt the elevating planes I and I' in unison to cause the aeroplane to 105 rise or to descend according to the direction in which the lever is moved at the time. The

upper and lower ends of the rods I^4 , I^5 are braced by suitable braces I^6 connected with the front and rear edges of the elevating planes I and I' , as plainly indicated in Fig. 3.

In order to steer the aeroplane to the right or to the left, use is made of two vertically-disposed steering rudders L , L' , of which the steering rudder L is located intermediate the elevating plane I and the propeller F , and the rudder L' is located intermediate the elevating plane I' and the propeller F' . The rudders L and L' have their upper and lower ends journaled at L^2 and L^3 in suitable bearings arranged on the extensions A' and A^2 of the main frame A . The rudders L and L' are provided with transversely-extending rods L^4 , L^5 connected by cables or other flexible connections N , N' with a lever O fulcrumed at O' on the carriage B and extending within convenient reach of the aviator seated on the seat D . Thus by the aviator imparting a forward or a backward swinging motion to the lever O the rudders L and L' are turned in unison to steer the aeroplane to the right or to the left according to the direction in which the lever O is moved at the time. Each of the rudders L and L' has a square lower portion while the upper portion is semi-circular.

In case of an accident to the motor or other vital part of the aeroplane use is made of a parachute P to permit the aviator to safely land without the aid of the motor and propellers. The parachute P is held centrally on the top of the main sustaining plane G and is in the form of a segment of a hollow sphere, as plainly indicated in Fig. 3, and the said parachute is provided with a stick P' extending downwardly and passing through an opening in the main sustaining plane G . The lower end of the stick P' supports a rope or a cable P^2 adapted to be fastened to a pin or cleat P^3 arranged on the framework A adjacent the aviator's seat D . By this arrangement the parachute P is held normally in inactive position on top of the main sustaining plane G . In order to move the parachute P into active position, that is, a distance above the main sustaining plane G , use is made of springs Q and R , of which the spring R is coiled on the stick P' and rests with its upper end on the under side of the parachute P . The lower end of the spring R bears on a runner R' mounted to slide on the stick P' . The spring Q is in the form of a flat spring doubled up and having one end fastened to the sustaining plane G near the center thereof and the other end of the said spring Q is fastened to a runner R' . Flexible limiting stops S , such as chains, cables or ropes connect the parachute P with the main sustaining plane G to hold the parachute P in extended position after the operator has released the flexible

connection P^2 from the pin or cleat P^3 . It is understood that normally the springs Q and R are under tension and when the parachute P is released as described then the springs Q and R force the parachute P upward into the extended position shown in dotted lines in Fig. 3, the upward movement of the parachute being limited by the flexible stays or stops S . By this arrangement the aeroplane is provided with an additional sustaining plane to ease the descent of the aeroplane in case of accident to its machinery or other vital part. It is understood that the controlling mechanism for the motor E is within convenient reach of the aviator seated on the seat D .

The planes G , H , I , I' , the rudders L , L' and the parachute P are suitably strengthened by a proper light skeleton frame work over which silk or other suitable textile material is stretched to form the desired plane. The outer portions of the main sustaining plane G are connected by rigid braces T as well as by flexible stays U with the side plane H to maintain the planes G , H and H' in proper position one relative to the other.

By arranging the various parts in the manner described an easy rising and descending of the aeroplane is had and by locating the main sustaining plane G in the manner described relative to the side planes H and H' and by making the said planes G , H and H' of the form indicated the equilibrium of the aeroplane is maintained at all times, especially when the aeroplane encounters heavy sidewise or contrary currents of air.

It is understood that by making the main sustaining plane of ovate form and with the sides curved downward the air resistance is concentrated toward the central part of the said main sustaining plane, thus insuring stability of the aeroplane. By the use of the side planes H , H' the carrying capacity of the aeroplane is correspondingly increased and a directive or linear impetus and steadiness is given to the aeroplane to relieve the aviator of undue nervous strain.

Having thus described my invention, I claim as new and desire to secure by Letters Patent:

1. An aeroplane, comprising a framework, a main sustaining plane mounted on the said framework and of an approximately oval shape and with the major axis extending in a transverse direction, and side planes arranged on opposite sides of the framework and disposed below the sides of the said main sustaining plane, the inner edges of the said side planes being straight and in close proximity to the sides of the framework, and the outer edges of the said side planes being of ovoidal shape, the front and

rear ends of the side wings projecting beyond the front and rear edges of the said main sustaining plane and the sides of the said main sustaining plane projecting beyond the sides of the said side planes.

2. An aeroplane, comprising a framework, a main sustaining plane mounted on the said framework and of an approximately oval shape and with the major axis extending in a transverse direction, and side planes arranged on opposite sides of the framework and disposed below the sides of the said main sustaining plane, the inner edges of the said side planes being straight and in close proximity to the sides of the framework, and the outer edges of the side planes being of ovoidal shape, the front and rear ends of the side wings projecting beyond the front and rear edges of the said main sustaining plane and the sides of the said main sustaining plane projecting beyond the sides of the said side planes, the said main sustaining plane being arched in a transverse direction and the said side planes being inclined upwardly and forwardly.

3. An aeroplane, comprising a framework, a main sustaining plane mounted on the said framework and of an approximately oval shape and with the major axis extending in a transverse direction, side planes arranged on opposite sides of the framework and disposed below the sides of the said main sustaining plane, the inner edges of the said side planes being straight and in close proximity to the sides of the framework, and the outer edges of the said side planes being of ovoidal shape, the front and rear ends of the side wings projecting beyond the front and rear edges of the said main sustaining plane, and the sides of the main sustaining plane projecting beyond the sides of the said side planes, and propelled wheels mounted on the said framework in front and rear of the said main sustaining plane and below the same and above the said side planes.

4. An aeroplane provided with a framework, a main sustaining plane mounted on the said framework, the said main sustaining plane being of an approximately oval shape and with the major axis extending transversely and the minor axis extending longitudinally and in a vertical plane passing through the longitudinal axis of the aeroplane, and side planes arranged on opposite sides of the framework and disposed below the sides of the said main sustaining plane, the front and rear ends of the side planes projecting beyond the front and rear edges of the said main sustaining plane, and the sides of the said main sustaining plane projecting beyond the sides of the said side planes.

5. An aeroplane provided with a framework, a main sustaining plane mounted on the said framework, the said main sustain-

ing plane being of an approximately oval shape and with the major axis extending transversely and the minor axis extending longitudinally and in a vertical plane passing through the longitudinal axis of the 70 aeroplane, the said main sustaining plane being arched in a transverse direction, and side planes arranged on opposite sides of the framework and disposed below the sides of the said main sustaining plane, the front 75 and rear ends of the side planes projecting beyond the front and rear edges of the said main sustaining plane, and the sides of the said main sustaining plane projecting beyond the sides of the said side planes; the 80 said side planes being inclined upwardly and forwardly.

6. An aeroplane provided with a framework, a main sustaining plane mounted on the top of the said framework, an open parachute above the said main sustaining plane, the said parachute having a stick extending downwardly and adapted to pass through an opening in the main sustaining plane, a spring coiled on the stick and resting with 90 its upper end on the under side of the parachute, a runner mounted to slide on the stick and against which the lower end of said spring bears, a V-shaped spring having one end fastened to the main sustaining plane, 95 and the other end to said runner, retaining means under the control of the aviator and connected with the said stick to hold the parachute normally in inactive position on top of the main sustaining plane and to hold the said springs under tension, the said retaining means when released allowing the springs to lift the parachute a distance above the main sustaining plane, and flexible stays connecting the parachute with the 100 main sustaining plane to hold the parachute in extended position.

7. An aeroplane provided with a framework, a main sustaining plane mounted on the said framework, an open parachute provided with a stick adapted to pass through an opening in the main sustaining plane, a V-shaped spring interposed between the said main sustaining plane and the said parachute, a coil spring on the said stick and interposed between the said parachute and the main sustaining plane, and flexible means connected with the said stick and adapted to be fastened to the framework to normally hold the said springs under tension and the 110 parachute resting on top of the main sustaining plane.

8. An aeroplane provided with a framework, a sustaining plane mounted on the said framework, an open parachute provided with a stick adapted to pass through an opening in the main sustaining plane, a V-shaped spring interposed between the said main sustaining plane and the said parachute, a coil spring on the said stick and 125 130

interposed between the said parachute and the main sustaining plane, flexible means connected with the said stick and adapted to be fastened to the framework to normally hold the said springs under tension and the parachute resting on top of the main sustaining plane, and flexible stays connecting the said parachute with the said main sustaining plane to hold the parachute in open position.

9. An aeroplane comprising a framework, a main sustaining plane mounted on the said framework, side planes arranged on opposite sides of the framework and disposed below the sides of the said main sustaining frame, the front and rear ends of the side planes projecting beyond the front and rear edges of the said main sustaining plane, and the sides of the said main sustaining plane projecting beyond the sides of the said side planes, propeller wheels mounted on the framework at the front and rear of the main sustaining plane and below the same and above the said side planes, 25 elevating planes at the front and rear of the framework, and steering rudders located

intermediate the elevating planes and the propeller wheels.

10. An aeroplane, comprising a framework including a carriage, a transversely extending main sustaining plane mounted on the framework above the carriage and arched in a transverse direction, side planes arranged on opposite sides of the carriage below the sides of the main sustaining plane, and having their inner edges straight and in close proximity to the sides of the carriage, the side planes being curved from the sides of the carriage in an outward and downward direction, the front and rear ends of the side planes projecting beyond the front and rear edges of the said main sustaining plane, and the sides of the main sustaining plane projecting beyond the sides of the said side planes.

In testimony whereof I have signed my name to this specification in the presence of two subscribing witnesses,

OLE CALUM.
